WORK SUPPORTING CARRIAGE

Howard E. Somes, Detroit, Mich., assignor to Budd
Induction Heating, Inc., Philadelphia, Pa., a
corporation of Michigan

Application May 15, 1944, Serial No. 535,680

3 Claims. (Cl. 308—3)

This invention relates to machine tools and other work performing equipment of the character having vertically reciprocable carriages for holding workpieces during the performance of work thereon.

The invention is particularly directed to that character of work supporting carriage in which spaced reciprocable side rods are interconnected at their ends by heavy cross heads having means, such as chucks, for supporting a workpiece between the side rods.

In order to accommodate workpieces of different lengths, it is desirable to so mount one of the heads that it can be moved on the side rods for movement to a predetermined adjusted position toward or away from the other cross head. When the carriage is vertically reciprocable and the cross heads are spaced a considerable distance apart, say, for example, eight or ten feet, considerable difficulty is encountered due to the weight of the cross heads, in effecting this adjustment.

It is the object of the present invention to provide in a machine having a carriage of the above character, novel means for supporting one of the carriage cross heads during movement of the other cross head relative thereto to an adjusted position, which means is simple in construction and can be expeditiously actuated into cooperative supporting relation with respect to the cross head to be supported.

With the foregoing and other objects in view which will be apparent from the following description to those skilled in the art to which the invention appertains, the present invention consists in certain features of construction and combinations of parts to be hereinafter described with reference to the accompanying drawings and then claimed.

In the drawings which illustrate a suitable embodiment of the invention:

Figure 1 is a front elevation of a heat treating machine selected for illustration of the invention;

Figure 2 is a side elevation of the machine shown in Figure 1;

Figure 3 is a transverse section taken approximately on line 3—3 of Figure 1;

Figure 4 is a fragmentary view of some of the parts shown in Figure 3 showing the cross head supporting means in cross head supporting position; and

Figure 5 is a vertical section taken approximately on line 5—5 of Figure 4.

Referring to the accompanying drawings, in 55

which like numerals refer to like parts throughout the several views, the machine selected for illustration is a heat treating machine for internally hardening the bore of an elongated tubular member 10. The machine base 11 in this case extends vertically and is formed with a relatively deep depression 12 in its front face which, in effect, provides spaced vertical columns 13.

10 Mounted on the face of each column 13 is a vertical rod 14 which is secured at its lower end in spaced relation to the column face by a suitable clamp 15. Although not shown in the drawings, the upper end of the rod 14 is secured in a similar manner to the upper end of the column 13.

The rods 14 form the guides for a vertically reciprocable carriage, generally designated 16, which include long cylinders 17 and upper and lower cross heads 18 and 19 respectively. These cross heads carry suitable chucking devices 20 and 21, respectively, for supporting the opposite ends of the workpiece 10 to be heat treated.

The cylinders surround the rods 14 which are 25 provided with cylinder portions 22 intermediate their ends and are reciprocably guided thereby. As is conventional practice in devices of this character, fluid under pressure is admitted to the cylinders at one side or the other of the pistons 22 to effect vertical movement of the carriage 16. Fluid admitted to the cylinders above the pistons 22 provides upper carriage movement whereas fluid admitted below the pistons 22 provides downward carriage movement.

30 In the machine shown, heating and quenching heads 23 and 24, respectively, are provided on the ends of supporting arbors 25 and 26 which after the workpiece 10 is in position are brought into the position shown and, in the operation of 40 this particular machine, the carriage moves the workpiece 10 longitudinally of the heating and quenching heads 23 and 24 during which movement the heating and quenching operations are performed.

45 Suitable cam bars 27, which form no part of the present invention, are secured through removable clamps 28 to the cylinders 17 and are used in controlling the operation of the machine. By removing the clamps 28 the cam bars 27 may be removed from the cylinders 17.

In order that the carriage 16 may accommodate workpieces of different lengths, the upper cross head 18 is made adjustable for movement on the cylinders 17 relative to the lower cross head 19 to any desired position. To this end,

the portions of the cross head 18 which surround the cylinders 17 are made in two parts to include inner clamping sections 29 and outer removable sections 30 which are secured to the inner sections by screws 31 in cylinder clamping relation. By loosening the screws 31, the clamping pressure is removed whereby the cylinders 17 and cross head 18 may be moved relative to each other.

In accordance with the present invention, a supporting means for the upper cross head 18 is provided in the form of a generally U-shaped bar 32 having spaced supporting bars 33 and an interconnecting cross piece 34. The bars 33 are slideable transversely of the columns 13 through recesses 35 formed in the columns 13 from a retracted position, as shown in Figure 3, to a forward position to underlie the carriage 18, as shown in Figures 4 and 5. The bars 33 are guided at their rearward ends between vertically spaced cross bars 36 which are secured by bolts 37 to the rearward side of the depressed region 12.

In order to accomplish the adjustment of the upper cross head 18, the cam bars 21, when used, are first removed. Then the carriage is elevated by its actuating mechanism for a slight distance, after which the carriage supporting device is moved forwardly to position the projecting ends of the bars 33 as shown in Figures 4 and 5, underneath the cross head 18. The carriage is then lowered until the cross head 18 rests upon the projecting ends of the bars 33. The machine screws 31 which clamp the sections 30 to the cross head are then loosened sufficiently to relieve the clamping pressure on the cylinders 17. The carriage may then again be actuated vertically upwardly whereby, since the upper cross head is supported on the bars 33 and is free from clamping engagement about the cylinders 17, the cylinders 17 are moved vertically upwardly through the cross head to the position necessary for obtaining the desired spacing between the chucks 20 and 21.

When this position is attained, the clamping screws 31 are tightened to again securely clamp the cross head 18 to the cylinders 17, after which upon elevation of the carriage the supporting bars may be retracted to the inoperative position shown in Figure 3.

It is obvious that the arrangement described is applicable to any vertically reciprocable carriage arrangement wherein an upper cross head is so arranged as to be released from secured engagement with its support for relative adjusting movement.

Various changes may be made in the detailed construction and arrangement of the parts described without departing from the spirit and substance of the invention the scope of which is defined by the appended claims.

What is claimed is:

1. In a machine for performing work on a workpiece, a vertically extending base portion, a vertically reciprocable carriage having a pair of vertically spaced cross heads thereon, vertical guide means on said base portion for guiding said carriage for vertical movement, the uppermost of said cross heads being slidably guided on said carriage for vertical adjustment toward and away from the lowermost of said cross heads, releasable means for clamping said uppermost cross head to said carriage, and extendable means carried by said base portion and being extendable to a position to support said uppermost portion independently of said carriage whereby upon release of said clamping means said carriage may be vertically moved relative to said uppermost cross head.
2. In a machine for performing work upon a workpiece, a vertically disposed machine base, a pair of spaced, parallel guide rods secured in vertical position to said base, a vertically reciprocable work supporting carriage supported on said guide rods for vertical movement relative thereto, said carriage having vertically spaced cross heads thereon, one of said cross heads being movable to an adjusted position on said carriage toward and away from the other, releasable means for clamping said one cross head in adjusted position to said carriage, and an extendable means carried by said base and being extendable to a position to support said one cross head against downward movement whereby upon release of said clamping means said carriage may be moved relative to said one cross head to change the spacing between said cross heads.
3. In a machine for performing work upon a workpiece, a vertically disposed machine base, a pair of spaced, parallel guide rods secured in vertical position to said base, a vertically reciprocable work supporting carriage including cylinder members vertically reciprocable on said guide rods and a pair of vertically spaced cross heads rigidly interconnecting said cylinder members, the uppermost of said cross heads being movable to adjusted positions on and longitudinally of said cylinder members toward and away from the other cross head, releasable clamping means for clamping said one cross head in adjusted position on said cylinder members, and an extendable means carried by said base and being extendable relative thereto to support said one cross head against downward movement whereby upon release of said clamping means said cylinder members and said other cross head may be moved relative to said uppermost cross head to change the spacing between said cross heads.

HOWARD E. SOMES.
